UNITED STATES PATENT OFFICE.

MARTIN L. ALSOP, OF NEW YORK, N. Y.

GEM-DISPLAY HOLDER.

1,012,501.

Specification of Letters Patent. Patented Dec. 19, 1911.

Application filed November 22, 1910. Serial No. 593,748.

To all whom it may concern:

Be it known that I, MARTIN L. ALSOP, a citizen of the United States, residing at New York, in the county of New York and § State of New York, have invented new and useful Improvements in Gem-Display Holders, of which the following is a specification.

This invention relates to an improved gem display holder and the leading object there- 10 of is to provide a gem display holder that can be manufactured very cheaply and which is formed with resilient gem clamping arms so arranged on the holder that a gem will be accurately centered thereon.

15 Another object of the invention is to provide a gem display holder having a body formed of a single strip of resilient material and provided with terminal portions formed into curved resilient arms and having gem clamping jaws and so arranged that 20 gems of various sizes will be positively gripped in position for display and accurately centered on the body of the holder.

A still further object of the invention is 25 to provide a gem display holder having a U-shaped finger engaging ring or band and resilient arms integral with said band and provided with terminal jaws adapted to grip a gem for display on a finger and so 30 arranged as to self center a gem, and means 35 slidable on the band and arms adapted to hold said jaws in positive gripping position and adapted to be moved to positions to hold the jaws for positive gripping when the holder is mounted upon a finger.

With the above and other objects in view 40 the invention relates to certain combinations, constructions and arrangement of parts clearly described in the accompanying draw- 45 ings, in which,

Figure 1 is a perspective view illustrating the application of the improved holder to a human finger. Fig. 2 is a perspective view of the holder removed and the jaws shown 45 in their open positions. Fig. 3 is an edge view of the holder with a gem in place be- 50 tween the jaws. Fig. 4 is a front elevation showing a gem in place between the jaws.

Referring to the accompanying drawings 55 1 denotes a body portion or strip of spring material, the central portion of which is bent into U-shaped form to provide a finger en- 60 gaging spring band having legs 2. The terminals of the legs 2 are bent outwardly and then inwardly to form lateral portions 3 65 adapted to be engaged by the finger and

thumb of the user and to form stops for the 70 slideable adjustment means.

Curved spring arms 4 extend from the lateral portions 3 and terminate in gem gripping jaws 5 which are provided with prongs 6. Clamping bands 7 are slideable on the legs 2 and the spring arms 4 and are adapted to move the jaws 5 toward each other or to hold said jaws positively in gripping posi- 80 tions when moved toward the central portion of the spring band.

When it is desired to arrange a gem for display on the holder pressure is applied upon the lateral portions or stops 3 so as to 70 move the terminals of the legs 2 toward each other and thereby move the gripping jaws away from each other, when a gem can be inserted between the gripping jaws. Pressure is then released from the stops and the 75 clamping bands are moved to their uppermost positions so as to positively grip the gem against accidental displacement. The holder may then be placed upon a finger and the action of mounting the holder upon the 80 finger will tend to force the band 7 along the legs 2 and the arms 4 so as to more effectively bind the gripping jaws against the gem.

The gripping jaws are arranged at equi- 85 distant points on either side of the central point of the holder so that a gem will be easily centered and positively held in its centered position on the holder. The improved gem holder is therefore a self center- 90 ing gem display device, and owing to the arrangement of the clamping bands 7 upon the spring arms and legs of the spring band the holder is a self adjusting one, as the act of mounting the holder upon a finger forces 95 the clamping bands into their uppermost or clamping positions and binds the gripping jaws against relative outward movement on the spring band, thereby preventing the possible customer from forcing the gem 100 from between the gripping jaws. When the high value of precious gems is considered the importance of this construction will be greatly appreciated.

By forming the holder out of a single 105 strip of spring material and providing the clamping bands for adjusting and binding the gripping jaws the device can be manufactured at a very low cost. No cutting points or surfaces are presented to the 110 wearer or to the operator, and it is not necessary for a jeweler to have any special

tools to adjust the gripping jaws or to bind them in their adjusted positions. The device also serves as a pick-up for gems and in this connection will be especially useful in handling very small gems.

Having thus described the invention, what is claimed is—

A gem display holder made of a single strip of resilient metal and bent to form a 10 U-shaped finger engaging member and terminal arms extending from said U-shaped member, said terminal arms being connected to said member by outwardly extending por-

tions and curved against the lugs of said U-shaped member and having gem gripping 15 jaws on their ends, said arms being normally held away from a U-shaped member and being adapted to be moved away from each other by applying pressure on the outwardly extending portions.

In testimony whereof I affix my signature in presence of two witnesses.

MARTIN L. ALSOP,

Witnesses:
